(57) **CLAIM**

The ornamental design of a rear bumper for automobiles, as shown and described.

DESCRIPTION

FIG. 1 is a front view of the rear bumper for automobiles showing my new design;

FIG. 2 is a bottom view of the rear bumper;

FIG. 3 is a right side view of the rear bumper; and,
FIG. 4 is a front perspective view of the rear bumper as seen from the left upper side.

The broken lines illustrate environmental structure only and form no part of the claimed design.
